UNITED STATES PATENT OFFICE.

EDWARD C. BEERS, OF ROCHESTER, NEW YORK, ASSIGNOR TO PHILLIPS & CLARK STOVE CO., INC., OF GENEVA, NEW YORK, A CORPORATION OF NEW YORK.

CONVERTIBLE GAS-FLEUE FOR COMBINATION GAS AND COAL RANGES.

1,337,112.

Specification of Letters Patent. Patented Apr. 13, 1920.

Application filed March 10, 1919. Serial No. 281,782.

To all whom it may concern:

Be it known that I, EDWARD C. BEERS, a citizen of the United States, residing at Rochester, in the county of Monroe and 5 State of New York, have invented certain new and useful Improvements in Convertible Gas-Flues for Combination Gas and Coal Ranges, of which the following is a specification.

10 The object of this invention is to construct the gas burner box of a bi-fuel range so that it may be heated either by gas burners or the product of combustion of the fire in the fire box of the range.

15 This and other objects of this invention will be fully illustrated in the drawings, described in the specification and pointed out in the claims at the end thereof.

In the accompanying drawings,

20 Figure 1 is a perspective view of the combination coal and gas range.

Fig. 2 is a vertical section through the gas burner box and coal flue of the range, the section being taken on the line 2^x—2^x of 25 Fig. 1.

Fig. 3 is a sectional view of the gas burner box and coal flue showing a modified form of construction of the convertible bottom of the gas burner box.

30 Fig. 4 is a perspective view of the range with the top thereof partly broken away.

Fig. 5 is a sectional view of the gas burner box and coal flue showing another modified form of construction of the convertible bottom 35 of the gas burner box.

In the several figures of the drawings, like reference numerals indicate like parts.

In the construction of the bi-fuel range shown in the accompanying drawings, the 40 ordinary four burner box is divided by means of a permanent and gas-tight partition into two smaller compartments or burner boxes, one of which is built so as to make it convertible into an auxiliary coal flue for the products of combustion from the fire box in the range to circulate therein. This arrangement permits the heating of 45 two of the holes in the top of the range by means of either gas or coal. In cold 50 weather, when the range is almost exclusively heated with coal, the burner box can

be converted into a part of the coal flue so that the holes leading out of the box are heated by the coal fire. In the six hole range shown in Fig. 1, four of these holes 55 can thus be heated by the coal fire while the two holes on the right-hand side are heated by gas burners. In this way the coal burned in the range may be utilized in an efficient manner for cooking, as well as for heating 60 purposes.

In warm weather, when the coal fire is not kept up in the range and all the cooking is done with the gas burners, this gas burner box, which has previously been used as an 65 auxiliary coal flue, may be reconverted for use with gas burners. Instead of the two holes on the right-hand side of the stove, four holes are thus made available for use in cooking with gas. The two holes on the 70 left-hand side of the range, which are located directly above the fire box, will then remain idle.

Thus the range shown in the drawings may have four holes exposed to the coal fire 75 and two holes exposed to gas burners in cold weather and as in warm weather four holes are available for cooking with gas, the two holes exposed to the coal fire may be left 80 idle or used.

In the drawings, reference numeral 1 indicates the fire box of the range. Leading from this fire box on one side thereof is the coal flue 2 which leads over the oven 3 and down at the side thereof as shown at 4. At 85 the bottom of the oven the hot gases from the fire box which pass over and down the oven 3 are deflected to the front of the oven by means of the baffle plate 5. After the gases have passed the baffle plate 5 they are 90 allowed to pass out through the rear of the flue into the chimney 6.

In order to heat the oven 3 by means of gas a false bottom 7 is inserted into the oven and is supported therein at a suitable distance above the floor of the oven. A gas burner 8 projects through the side of the oven between the floor proper and the false bottom thereof. This burner is used to heat the oven when the range is not heated by 100 coal fire.

Mounted above the coal flue 2 are the gas

burner boxes 9 and 10. These burner boxes are adapted to receive suitable gas burners (four in number) which are held in place below each of the holes 11, 12, 13 and 14 in the top of the range. Both of the burner boxes are thus utilized for cooking with gas.

The burner box 9 with two openings is convertible into an annex to the coal flue by opening the bottom of it to let the products of combustion from the fire in the fire box circulate in it and supply heat to the holes 11 and 12 in the top of the range.

For this purpose the burners which are mounted below each of the holes 11 and 12, 15 are removed. The bottom of the burner box 9 is made in two sections 15 and 16 which swing on the hinges 17 and 18 respectively. Mounted in front of the burner box 9 is the swinging front plate 19. The 20 front of the burner box is ordinarily left open for the insertion of the gas burners and the admission of the necessary air for the combustion of the gas as it issues from the burners. This front is closed by the 25 front plate 19 when the sections 15 and 16 of the bottom of the burner box 9 are opened, which is done by swinging each of these sections to the dotted line position shown in Fig. 1. When moving into this 30 position the front plate 19 which rests on top of the sections 15 and 16 is lifted by them and is swung into the dotted line position shown in Fig. 2 and is held in this place while the bottom of the burner box 35 is open. The front of the burner box is hermetically closed by the front plate 19 while at the same time the bottom of the burner box is kept open. It is understood that the gas burners which are removable 40 must first be removed from the burner box before the bottom of it can be opened and the front of it closed.

When the burner box 9 is open at the bottom and the front of it is closed the 45 products of combustion from the fire in the fire box will circulate in it and heat the top of the burner box. This arrangement in the range permits the use of the range for cooking with coal not only on the holes 20 and 21, which are located directly above the fire box, but it also allows heating of the 50 holes 11 and 12 by the same coal fire instead of by gas as previously described.

To deflect the products of combustion into the burner box 9 after the bottom of it has been opened, a damper 22 is mounted in the flue 2. This damper is made up of two sections which are mounted near the middle of the flue and are adapted to swing therein 60 and be set at any angle to the direction of the flow of the products of combustion.

The damper is set at an angle to the bottom of the flue in order to more readily deflect the gases upward into the gas burner 65 box. See Fig. 1.

The construction above described is capable of modifications, some of which are shown as follows:

In Fig. 5 the sections 40 and 41 are mounted to swing in such a manner that 70 the section 40 will swing in the same direction as the section 41 and overlap the section 41 as shown in dotted lines in Fig. 5.

Instead of providing the bottom with swinging doors or sections for the purpose 75 of opening it, a slide may be used as shown in Fig. 3. This slide comprises the bottom of the burner box and is drawn to the front of the range to open the burner box from below. 80

It will be understood that with each of the modified constructions shown in the several figures the front of the burner box must be closed with the front plate 19 when the bottom of the burner box is opened. 85

I claim:

1. In a bi-fuel range, the combination of a draft flue, a gas burner box provided on top of said flue, and means for admitting the products of combustion passing through 90 said draft flue into the bottom of said gas burner box.

2. In a bi-fuel range, the combination of a draft flue, a gas burner box provided on top of said flue, said box having an open- 95 ing leading into said flue from above, and a door for closing said opening, whereby, on the opening of said door, the products of combustion in said flue are admitted into said box. 100

3. In a bi-fuel range, the combination of a draft flue, a gas burner box provided on top of said flue, said gas burner box having an opening leading into said flue from above, 105 said gas burner box having a second open- 110 ing leading to the outside of the range, and means for opening and closing both of the openings in said gas burner box.

4. In a bi-fuel range, the combination of a draft flue, a gas burner box provided on 110 top of said flue, gas burners mounted in said gas burner box, said gas burners being removably mounted in said gas burner box, 115 said gas burner box having one opening leading into said flue from above and another opening leading to the outside of the range for the admission of said gas burners, and means for simultaneously closing the opening leading from the outside of the range and opening the opening leading into 120 said flue.

5. In a bi-fuel range, the combination of a draft flue for the coal fire pot, a gas burner box on top of said flue, said box normally excluding therefrom the products 125 of combustion passing through the flue, and means for making the box a part of the flue so as to pass the products of combustion of the fire pot into or through the box.

6. In a combination coal and gas range, 130

the combination of a coal flue, a burner box mounted above said coal flue, means for opening said burner box to bi-pass the products of combustion from said flue 10 through said burner box.

7. In a combination coal and gas range, the combination of a coal flue, a burner box

mounted above said coal flue, means for opening said box, and means for deflecting the products of combustion from said flue 10 through said burner box into said flue.

In testimony whereof I affix my signature.

EDWARD C. BEERS.
